UNITED STATES PATENT OFFICE.

GEORGE BECK, OF ELDRED, NEW YORK.

BOILER-PEDESTAL.

SPECIFICATION forming part of Letters Patent No. 249,722, dated November 15, 1881.

Application filed April 14, 1881. (No model.)

To all whom it may concern:

Be it known that I, GEORGE BECK, of Eldred, county of Sullivan, and State of New York, have invented a new and useful Improvement in a Boiler-Pedestal, of which the following is a specification.

It frequently occurs that the pedestals or columns that are made to support the boilers of kitchen-ranges have to be cut off to permit the boiler to stand under the ceiling of the kitchen; consequently, if said column be formed in an ornamental style and a portion of its lower end be removed, its symmetrical effect is more or less injured.

It is the object of this invention to overcome this difficulty; and it consists in providing a raised or convex base-plate for the lower end of the pedestal or column that supports the boiler of kitchen-ranges, and forming the central or raised portion of said plate with a number of circular shoulders, like steps or terraces, each one of which corresponds to some section of the pedestal, and so forming the lower portion of the pedestal or column that a certain portion may be removed without materially injuring its form, and at the same time it will have a proper support on some one of the said shoulders, as will hereinafter appear.

The drawing represents an elevation of the stand and its base, but with a portion broken out to show a section of the parts.

At A is represented a base-plate for supporting the pedestal or column of a kitchen-boiler, as at B. Said plate is raised in a convex form, as shown, and around its central por-

tion are formed a number of circumferential shoulders or rabbets, like steps or terraces, as at C C C, one above another, from the largest and lowest one to the smallest and highest one. The column is so designed that some section 40 of it will fit upon one of the said rings or steps, and consequently, if the workman finds the pedestal too high to permit the boiler to stand under the ceiling, he can cut or break off a portion of the lower end, as indicated by the 45 grooves at D D' D² D³, &c., until it is short enough, and then the end so shortened will find a resting-place upon some one of the said steps, and the symmetrical appearance of the column and base will not be materially injured thereby, and one not familiar with the construction 50 would not know that the column or pedestal had been reduced in height.

I therefore claim—

A pedestal for kitchen-boilers, composed of 55 a raised or convex base having a series of shoulders or steps and a cone-shaped column, having at intervals circumferential grooves, the diameter of each section of the column at these points being the same as that of some one 60 of the steps of the base, whereby the column will fit upon said base when a section of the column is removed, as hereinbefore set forth.

In witness whereof I have hereunto set my hand and seal in the presence of two subscribing witnesses.

GEORGE BECK. [L. S.]
